BAG FRAME STRUCTURE

Joseph F. Cox, Arlington, Mass., assignor to
United-Carr Fastener Corporation, Cambridge,
Mass., a corporation of Massachusetts

Application February 5, 1936, Serial No. 62,449

1 Claim. (Cl. 150—29)

My invention relates to improvements in hinging devices for the frames of hand bags and the like containers.

In the drawing, which represents a preferred embodiment of my invention:

Fig. 1 is a plan view of a hand bag frame structure including an outer frame having an inner purse frame secured thereto;

Fig. 2 is an enlarged view of my improved outer and inner frame hinging members with the frames in assembly with each other;

Fig. 3 is a section of the installation shown in Fig. 2, the outer frame hinging member being shown in elevation;

Fig. 4 is a side elevation of the outer frame hinging member ready for the flange-forming operation upon the same;

Fig. 5 is a side elevation of the member shown in Fig. 4 after the flange-forming operation;

Fig. 6 is a side elevation of the purse frame hinging member ready for the bead-forming operation upon the same;

Fig. 7 is a side elevation of the member shown in Fig. 6 after the head-forming operation;

Figs. 8 and 9 are sectional views, partly in elevation, showing one method by which the outer frame hinging member is secured with the outer frame members; and

Figs. 10 and 11 are sectional views, partly in elevation, showing one method by which the purse frame hinging member is secured with the purse frame members.

Referring to the drawing, Fig. 1 shows a preferred hand bag structure including an outer frame 1 and a purse frame 2. The outer frame 1 comprises a pair of frame members having a set of adjacent leg portions 3 and 4 at opposite ends of the frame. The leg portions of each set are hinged together at their free ends, as best illustrated in Figs. 2 and 3. The purse frame 2 comprises a pair of frame members having a set of adjacent leg portions 5 and 6 at opposite ends of the frame and hinged together at their free ends (Figs. 2 and 3).

Referring in detail to my improved frame hinging construction, as most clearly illustrated in Figs. 2 and 3, it will be noted that I have chosen to construct the outer frame in such a way that the free end of the leg portion 3 is provided with an integral hollow bearing 7 and the free end of the leg portion 4 is provided with an ear-shaped element 8 having an aperture therethrough in line with the opening in the hollow bearing 7, as shown in Fig. 3. The elements 7 and 8 are pivotally held together at each end of the frame 1

by a solid pin member 9. The pin member, before assembly with the elements 7 and 8, is of a form substantially as shown in Fig. 4 being of one-piece construction having a head 10 at one end and a longitudinal shank 11 extending from the head and ending in an attaching portion 12 of smaller diameter than the shank 11 and preferably having a free end 12a of rounded form so that no sharp edge will be presented thereby. A shoulder 13 is formed on the shank 11 at the junction of the shank with the attaching portion.

In assembling the pin member with the ends of the leg portions of the outer frame, the pin is first inserted through the hollow bearing 7 and the element 8 so that the pin head 10 will lie adjacent to one end of the bearing 7 and the attaching portion 12 and a portion of the shank 11 will extend beyond the ear-shaped element 8. Next, a suitable tool 20 having a sharp cutting edge 20a is brought down upon the shoulder 13 (Figs. 8 and 9) with the result that the material of the shank 11 adjacent to the shoulder is swaged or rolled back to form a peripheral flange 14 which extends around the shank 11. In my preferred form, this flange 14 engages the outside surface of the ear-shaped element 8 (Fig. 9). The attaching portion 12 is lengthened by the action of the tool for a relative distance depending upon the amount of material taken from the shank 11 to form the flange.

After the tool operation, above described, the pin member, in the form shown in Fig. 5, extends the width of the frame. The hollow bearing 7 and the ear-shaped element 8 bear upon the entire surface of the shank 11 and freely pivot about the same. The elements 7 and 8 are maintained in compact assembly with the shank of the pin between the head 10 and the flange 14, as shown in Fig. 3. The attaching portion 12 extends inwardly toward the set of legs at the opposite end of the frame for reasons which will be hereinafter more fully described.

The adjacent leg portions 5 and 6, at opposite ends of the purse frame 2, have the ear-shaped elements 15 and 16 formed integral with the free ends thereof. The elements are pivotally held together by a hollow rivet means 17 which is of a form, before assembly with the frame, substantially as shown in Fig. 6 having a head 18 and a longitudinal tubular shank 19 which is provided with an opening at the end opposite the head 18. In assembling the rivet with the purse frame, the rivet is passed through apertures in the ear-shaped elements 15 and 16 (Fig. 10) so that the head will lie adjacent to the outside surface of

the element 16. While the parts rest on a tool, not shown, a tool 21 is brought down upon the shank (Figs. 10 and 11) in a way to collapse the shank between the end of the tool 21 and the ear 15 thereby to form a peripheral bead 22 at a predetermined position on its length so that the bead will lie adjacent to the outside surface of the element 15 (Figs. 3 and 11). It will be noted that the tool (Figs. 10 and 11) which I have used to form the ridge is shaped to provide a circumferential part 23 which is adapted to enclose the outside surface of the rivet shank to prevent outward buckling of the same except where desired. At the same time that the part 23 engages the outside surface, a central tool part 24 engages the inside surface of the hollow shank for the purpose of preventing any inward bending of the shank when downward pressure is exerted by the tool upon the free end 19^a. After the bead is formed by the operation, as described, the elements 15 and 16 are compactly assembled with the shank, between the head 18 and the ridge 22, and capable of pivoting freely upon the shank (Fig. 3). The open end of the shank 19 extends outwardly in a direction away from the set of arms located at the other end of the frame.

To assemble the purse frame 2 with the outer frame 1, the open end of a rivet shank at one end of the purse frame is slipped over the attaching portion of one of the hinge pin members extending from the outer frame. The purse frame is then pressed toward the attaching portion whereby the natural spring action in the frame will allow the open end of the shank at the other end of the purse frame to be slipped over the corresponding pin extending from the outer frame whereupon the purse frame will spring back to normal position and the parts will

be secured together, as shown in Fig. 3. When the frames are assembled with each other, the attaching portion of each pin will extend for a sufficient distance into the rivet shank to prevent any chance of unintentional separation of the frames.

As a result of my improved hinging members, I am enabled to hinge together adjacent legs at opposite ends of inner and outer frames in a highly efficient and inexpensive way necessitating a minimum of parts as compared with the commercial hinge constructions now in use.

Although I have illustrated and described a preferred embodiment of my invention, I do not wish to be limited thereby, because the scope of my invention is best defined by the following claim.

I claim:

In a pivoted frame structure for devices of the class described, a one-piece hollow hinge pin having a head at one end thereof, a shank extending from said head, said shank having a substantially uniform diameter throughout its length, said diameter of said shank being less than that of said head, said shank passing through parts of said frame and acting as a pivot bearing, a peripheral bead extending outwardly from said shank and disposed on the length of said shank in spaced relation to said head whereby said bead and said head cooperate to hold the frame parts together, a portion of said shank on the other side of said bead from said head disposed outside of said hinged portions of the frame structure for cooperation with the hinge pin means of a cooperating frame structure.

JOSEPH F. COX.
